UNITED STATES PATENT OFFICE.

CLARENCE L. WATSON, OF ATTLEBOROUGH, MASSACHUSETTS, ASSIGNOR
TO THE WATSON & NEWELL COMPANY, OF SAME PLACE.

DESIGN FOR A SPOON.

SPECIFICATION forming part of Design No. 31,732, dated October 31, 1899.

Application filed October 7, 1899. Serial No. 732,971. Term of patent 14 years.

To all whom it may concern:

Be it known that I, CLARENCE L. WATSON, a citizen of the United States, residing at Attleborough, in the county of Bristol and State 5 of Massachusetts, have invented and produced a new and original Design for a Spoon, of which the following is a specification, reference being had to the accompanying drawings, forming part thereof.

10 Figure 1 is a side view of a spoon, showing my design. Fig. 2 is a plan view of the under or reverse side of the spoon.

As shown in the drawings, the leading and material features of my design consist in the 15 curved handle extending from one end of the bowl and a loop extending from the neck of the handle to the junction of the handle with the bowl, as will be more fully set forth hereinafter.

20 In the drawings, *a* indicates the bowl of the spoon; *b*, the neck of the handle; *c*, the blade

of the handle, and *d* a loop extending from the junction of the blade of the handle with the neck in a slightly more than semicircular curve and extending in a flattened curve to 25 the junction of the handle with the bowl. The blade of the handle extends beyond the loop and presents the conventional appearance.

Having thus described my invention, what 30 I claim as new, and desire to secure by Letters Patent, is—

The design for a spoon herein shown and described.

In testimony whereof I have signed my 35 name to this specification in the presence of two subscribing witnesses.

CLARENCE L. WATSON.
